UNITED STATES PATENT OFFICE.

ARTHUR A. LAWRY, OF VALDOSTA, GEORGIA.

APPARATUS FOR CASTING GOLD INLAYS.

1,290,250.

Specification of Letters Patent.

Patented Jan. 7, 1919.

Application filed June 4, 1918. Serial No. 238,154.

To all whom it may concern:

Be it known that I, ARTHUR A. LAWRY, a citizen of the United States, residing at Valdosta, in the county of Lowndes, State of Georgia, have invented a new and useful Apparatus for Casting Gold Inlays; and I do hereby declare the following to be a full, clear, and exact description of the invention, such as will enable others skilled in the art 10 to which it appertains to make and use the same.

This invention relates to an improved apparatus for casting gold inlays.

One of the objects of the invention is to 15 provide an improved machine or apparatus of this kind, in which the force of gravity is utilized.

A further object of the invention is to provide an improved, simple, efficient and practical machine of this kind, which may be manufactured at a small cost and sold at a reasonable profit.

One of the features of the invention consists in the provision of a frame, a forked 25 lever pivotally mounted thereon, and an inlay investment cup, adapted to coöperate with a receiving cup containing moistened material, whereby the steam generated from the heat of the metal, adapted to be contained in a conical container, may force the metal through an orifice in the bottom of the container, into a form in the inlay investment.

A further object of the invention is to provide a machine of this kind which may be constructed of any suitable material, the frame of which being lined with asbestos, to avoid heating the frame excessively during constant use.

40 In practical fields the details of construction may necessitate alterations falling within the scope of what is claimed.

The invention comprises further features and combination of parts as hereinafter set 45 forth shown in the drawings and claimed.

In the drawings:—

Figure 1 is a view in side elevation of the improved machine constructed in accordance with the invention.

50 Fig. 2 is a plan view.

Fig. 3 is a longitudinal sectional view on line 3—3 of Fig. 2.

Fig. 4 is a transverse sectional view on line 4—4 of Fig. 2.

55 Fig. 5 is a detail view of a container or holder, which at one time may hold the wax

inlay and at another time contain the gold for forming the inlay.

Referring more especially to the drawings 1 designates the frame of the machine as a 60 whole which comprises a base 2, and an arch portion 3. This arch consists of the side standards 4 and a top piece 5. The side standards are secured to the longitudinal edges of the base by means of screws 6 while 65 the upper ends of the standards are secured by screws 7 to the top piece or section. The upper face of the base 2 and the inner faces of the side standards, and the under face of the top section are lined respectively with 70 pieces of asbestos 8, 9 and 10. A suitable receiving cup 11 is secured by screws 12 to the under face of the asbestos piece 10 of the top section 5. The inner cylindrical wall of the receiving cup is provided with an annular 75 rib 13. This receiving cup is designed for the reception of any suitable moistened material 14, such as moldine, which is composed principally of a kind of clay worked with glycerin. The annular rib 13 constitutes 80 means to retain the moistened material in said receiving cup. A forked standard 15 is secured by screws 16 to the base whereby it may extend vertically. A lever 17 is pivoted by means of the pin 18 between the forks of 85 said standard 15. A guide bracket 19 is also secured to the base by means of the screws 20, with the asbestos piece 8 between the guide bracket and the base 2. This bracket comprises upstanding guide arms 21, between which the longer arm 22 of the lever 17 is guided. The extremity of the longer arm terminates in forks 23, in bearings of the extremities of which the laterally extending diametrically arranged axially 90 alined pins 24 of the inlay investment cup 25 are fulcrumed, so that when the shorter arm of the lever is depressed, the inlay investment cup will uniformly engage the moistened material or moldine in the receiving cup. In constructing or molding gold 95 inlays, the cavity is first ground and cleaned, after which a wax impression is taken of the cavity. The inlay investment in the cup 25 is then heated to a softened condition. The wax impression of a cavity is then mounted in the usual manner upon a pin (not shown), but which may be supported in the orifice 26 of the holder 27. The holder is then mounted upon the investment cup, so that the wax 100 impression may extend into the inlay investment. The inlay investment is then al-

105
110

lowed to harden, and subsequently to which, the wax impression is then melted by heat from any suitable source, preferably a blow torch, and then removed, thereby forming a cavity in the investment corresponding in shape and configuration to that in the tooth. The pin, which is supported in the orifice 26, having first been removed, and the gold which is placed in the conical concavity 28 of the holder 27, is brought to a molten state by applying heat thereto from any suitable source preferably blow-torch, whereby the molten gold may pass through the orifice 26 into the cavity of the investment to form the inlay. The short arm of the lever 17 is then depressed, whereby the marginal edge of the investment cup is brought into uniform contact with the moistened material or moldine in the receiving cup, and through the medium of steam pressure generated from the heat from the molten metal on the moistened material, the gold in the holder is forced through the orifice 26 into the cavity of the inlay investment, whereby a gold inlay suitable to enter the cavity of the tooth is constructed or molded.

The invention having been set forth what is claimed as new and useful is:—

1. In a machine for molding gold inlays, the combination with a frame having an arch part, of a receiving cup containing moistened material secured to the under part of the arch, of a gravity lever pivotally mounted upon the base of the frame, and an inlay investment cup fulcrumed upon the gravity actuated end of said lever, to coöperate with the moistened material of the receiving cup, for forming gold inlays.

Copies of this patent may be obtained for five cents each, by addressing the "Commissioner of Patents, Washington, D. C."

2. The combination with a frame comprising a base and an arch portion, of a lever provided with a gravity actuated end pivotally mounted upon the base, guiding means for the gravity actuated end, an inlay investment cup fulcrumed on the extremity of the gravity actuated end, a receiving cup secured to the under face of the arch and adapted to contain a moistened material, with which the inlay investment cup uniformly engages, whereby gold inlays are molded through the medium of steam pressure.

3. The combination with a frame comprising a base and an arch portion, of a lever provided with a gravity actuated end pivotally mounted upon the base, guiding means for the gravity actuated end, an inlay investment cup fulcrumed on the extremity of the gravity actuated end, a receiving cup secured to the under face of the arch and having on the inner circumference of the cylindrical wall an annular rib for retaining therein a moistened material, with which the inlay investment cup uniformly engages, whereby gold inlays are molded through the medium of steam pressure, the upper face of the base and the inner upper and side walls of the arch being respectively lined with asbestos to avoid excessively heating the frame.

In testimony whereof I have signed my name to this specification in the presence of two subscribing witnesses.

ARTHUR A. LAWRY.
